INDICATOR

Filed Oct. 26, 1929

UNITED STATES PATENT OFFICE

RICHARD HUBERT DES CHAMPS, OF MONTREAL, QUEBEC, CANADA

INDICATOR

Application filed October 26, 1929, Serial No. 402,766, and in Canada September 18, 1929.

My invention relates to an indicator.

An object of this invention is to provide a very useful device that will be a great convenience and time-saver to housewives and 5 milkmen, and easy and cheap of manufacture.

Another object is to provide a very effective advertising medium.

Another object is to so design such an indicator that it will provide a large effective 10 space for tabulated items, given a device of certain maximum dimensions, and which can be made applicable to different requirements; and generally, the objects of my invention, 15 are to improve on known indicating devices.

In the drawings:

Figure 1 is a front view of an indicator made in accordance with my invention;

Figure 2 is a rear view of Figure 1;

Figure 3 is a section on line 3—3 in Figure 1;

Figure 4 is a section on line 4—4 in Figure 3.

Like numerals of reference indicate corresponding parts in the various figures.

Referring by numerals to the drawings, and particularly to Figure 1, the indicator consists essentially of a main member 10, preferably flat and shaped to represent a 30 bottle or other object, and of one or more pointer members 13 and 13A mounted to slide over the member on which are printed a list or table of items.

As shown, the tabulated items are printed 35 or painted crosswise on one face of the indicator and relate to such products as are usually supplied by the milkman; other words may be used, such as "Come in" or "Ring the bell," etc., according as required.

This indicator, while primarily useful as a 40 "milk and cream" indicator, may also be adapted to other uses.

This indicator member 10 may be made of any suitable material, such as wood or 45 cardboard, and may be hung from a door knob or from the neck of a milk bottle, by providing a looped string 12 passed through a hole 11 in the top of the indicator. The member 10 is formed with two parallel longitudinal edges to slidably receive pointer

members 13 and 13A, the edges being preferably covered with U-shaped metal runners 16 when the main member 10 is made of a soft substance such as cardboard. Such runners will act not only as tracks for the 55 pointers but will also serve to stiffen the device and prevent it from buckling or bending.

The pointers, of which two are shown, and the number of which may be one only, or more than two, according to exigencies, are 60 turned rearwardly and inwardly at the ends (see Figure 3) to form lugs 15 engaging the edges and rear face of the indicator, or more particularly of the runners 16, when such are used; thus, the pointer members are held 65 on the runners by friction and can be made to slide up and down to their desired or selected "indicating" positions. For instance, referring to Figure 1, the pointer 13 is shown in a position to indicate that 1 quart of milk 70 is required, whereas the pointer 13A is in a "neutral" position.

The pointers are preferably formed with a centrally-located finger tab or ledge 19, (see particularly Figures 3 and 4) whereby 75 to facilitate the sliding of the pointers from one position to another.

A ticket holder 17, made of some suitable substance such as leather, may be provided as shown clear of the pointers and fastened to 80 the member 10 as with metal staples 18.

The rear face of the device may be utilized for advertising purposes, as shown in Figure 2, or it may be used for printing the same items but in another language, as appear on 85 the front face, in which case the pointers would take the form of flat closed loops by extending the lugs 15 until they meet.

It will be noted that as the pointers are 90 mounted to slide up and down over the tabulated items, a number of such pointers may be used without one interfering with the other and a maximum effective display space thus obtained.

It is to be understood that the device may 95 be varied in form but I wish to secure all such forms or modifications as fall within the scope and spirit of the appended claims.

What I claim is:

1. An indicator comprising a main member 100

having parallel longitudinal edges and adapted to have tabulated items arranged crosswise thereon, runners secured over the parallel edges of said main member, and a crosswise pointer member slidably mounted on said runners and friction-held thereon in selective positions.

2. In an indicator, a main member having parallel longitudinal edges and adapted to have tabulated items arranged crosswise thereon, and a crosswise pointer member having the ends turned rearwardly and inwardly to slidably and frictionally engage said edges and a portion of the rear of said member.

15. Signed at the city of Montreal, this 11th day of October, 1929.

RICHARD HUBERT DES CHAMPS.
